FEED CARRIAGE FOR STENCIL CUTTING MACHINES

Filed April 17, 1922

Patented Jan. 6, 1925.

1,521,898

UNITED STATES PATENT OFFICE.

WALT C. MARSH, OF BELLEVILLE, ILLINOIS.

FEED CARRIAGE FOR STENCIL-CUTTING MACHINES.

Application filed April 17, 1922. Serial No. 553,438.

To all whom it may concern:

Be it known that I, WALT C. MARSH, a citizen of the United States, residing at the city of Belleville, county of St. Clair, and 5 State of Illinois, have invented a new and useful Feed Carriage for Stencil-Cutting Machines, of which the following is a specification.

This invention relates to improvements in 10 feed carriages for stencil cutting machines, and consists in the novel construction hereinafter disclosed.

An object of the invention is to provide 15 a feed carriage for a stencil cutting machine arranged to be stepped laterally across the bed of the machine in stencil cutting operations, and being provided with mechanism operable incident to the return of the carriage to normal position for moving the 20 stencil sheet support forward for line spacing.

Another object of the invention is to provide 25 a feed carriage for stencil cutting machines having an adjustment to and from cutting point of the machine, with mechanism for automatically moving the stencil sheet support forward incident to a return movement of the carriage, said mechanism being operable in the reverse direction 30 manually for adjustment of the stencil sheet in intermediate positions.

Another object of the invention is to provide 35 in connection with a feed carriage for stencil cutting machines a novel means for clamping the stencil sheet in the stencil sheet support of the carriage.

Additional detailed advantages of the 40 construction will be apparent from the following description taken in connection with the accompanying drawing, in which—

Fig. 1 is a plan view of the carriage embodying the invention.

Fig. 2 is a bottom plan view thereof.

Fig. 3 is a detailed view of a portion of 45 the mechanism for stepping the stencil sheet support forward.

Fig. 4 is a vertical section taken on the line 4—4 of Fig. 1.

Fig. 5 is a vertical section taken on the 50 line 5—5 of Fig. 1.

In the embodiment of the invention illustrated in the drawing the carriage is made up of a plate 1 having a spaced series of depressed teeth 2, the series of teeth 2 constituting a rack which is a part of the trans- 55 verse feed mechanism whereby the carriage

is stepped across the bed of the machine by suitable mechanism comprising a part of the stencil cutting machine proper and which is not illustrated as it forms no part of the 60 present invention.

The carriage also includes a plate 3 arranged on the top face of the plate 1, the plate 3 being of less width than the plate 1 so as to form a recess whereby the carriage 65 is mounted on rails of the stencil machine bed so that it will ride across the bed in true alinement. The carriage also includes a top plate 4 that constitutes a support for the stencil sheet. The three plates 1, 3 and 4 70 are riveted together at spaced intervals by rivets 5.

A casting 6 is supported on the left end of the plate 4, said casting constituting a housing for the stencil sheet support operating 75 mechanism and also a housing for the stencil sheet support.

The stencil sheet support includes an elongated rack plate 7 having rack teeth 8 on its outer edge and a lateral plate 9 extending 80 inwardly from the plate 7. A spring plate 10 is secured to the upper face of the plate 9 near its rearward edge by screws 11. This plate 10 is flexed slightly upwardly at the central portion and is flared outwardly at 85 its forward end. The stencil sheet 12 is received between the forward edge of the plate 10 and the upper face of the plate 9 and is clamped in position by a clamping device comprising a thimble 13 mounted on a stud 14 supported in the plate 9. The thimble 13 has a lateral projection or tooth 15 across its bottom face, said tooth seating in a depression 16 formed in the upper face of the plate 10. The thimble carries an arm 17 so that 90 the thimble may be turned on the stud 14. In the position shown in Fig. 5 the thimble is so turned that the tooth 15 seats in the recess 16 in which position the spring plate 10 is raised at its forward end from the face 95 of the plate 9 for the insertion of the stencil sheet. By turning the arm 17 to the position shown in Fig. 1 the tooth 15 is across the depression 16, clamping the spring plate 10 downwardly at its forward end against 100 the stencil sheet. The spring plate 10 may be provided with teeth 18 near its forward edge, which teeth impinge against the stencil sheet and securely hold the same in the stencil sheet support.

The casting 6 has located at its inner edge 110 a stepped recess 19 in its under face, the

base of said recess being of less width than the lower portion thereof. The plate 7 has riveted to its upper face a plate 20, the plate 20 having oblique slits 21 therein so as to 5 form tongues 22 that spring outwardly from the sides of the plate. The casting 6 fits over the plates 7 and 20 so that the plate 20 rides in the narrow portion of the recess 19, while the plate 7 extends in the wider portions 10 of the recess 19. It will be noted that the inner wall of the recess 19 terminates at the base of the narrow portion of the recess so that the lower face of the wall, constituting the inner wall of the narrow 15 portion of the recess 19 rides against the upper face of the plate 7 adjacent to the inner edge of the plate 20. The outward spring of the tongues 22, which it will be noted are arranged on each side of the plate 20, frictionally engage against the side walls of the narrow portion of the recess 19 so as to hold the stencil sheet support in proper alignment in a forward and backward direction, so that it requires some power to move 25 the stencil sheet support in either a forward or backward direction, thus preventing the movement of the stencil sheet support from its adjusted position by the mere operation of the machine in the lateral stepping of 30 the carriage across the machine. In other words, sufficient rigidity is imparted to the stencil sheet support to hold it in its adjusted position, thereby preserving the stencil sheet in proper alignment during the cutting 35 operation of the machine.

It will be noted that there is an elongated slot 23 in the bottom wall of the recess 19 of the casting 6. A stud 24 attached to the plate 20 projects through the slot, said stud 40 24 being formed with a finger piece at its top whereby the stencil sheet support may be manually moved toward and away from the cutting point of the machine for manual adjustment of the stencil sheet. 45 The carriage is provided with mechanism operable incident to the lateral movement of the carriage to normal position for stepping the stencil sheet support forward. This mechanism includes a stud 25 that extends through and is supported by the plates 50 1, 3 and 4, said stud extending upwardly through a housing 26 formed in the casting 6.

A gear wheel 27 is revolvably mounted on 55 the stud 25, said gear wheel being within the housing 26 of the casting 6 and in mesh with the rack 8. The gear wheel 27 has attached to its upper face a ratchet wheel 28, said ratchet wheel having a series of spaced 60 teeth formed thereon and with which a pawl 29 cooperates for imparting an intermittent rotary motion to the gear wheel 27, thereby moving the stencil sheet support forward spaced distances. The pawl 29 carries a 65 spring 30 which abuts against the side wall

of the housing 26 and serves to hold the pawl in contact with the ratchet wheel 28. Within the housing 26 is an abutment 31 for the tail of the pawl 29, which abutment limits the return movement of the pawl so as to effect the proper engagement thereof with the teeth of the ratchet 28. A handle comprising a bell crank lever having a long arm 32 and a short arm 32^a is pivoted on the stud 25, the hub 33 of the lever fitting over the stud 25. The bell crank lever is provided with a hand piece 34 for manual engagement and the short arm of the lever carries a pin 35 that passes through a slot 36 in the upper wall of the housing 26, said pin carrying the pawl 29 at its other end so that the pawl pivots on said pin 35.

Obviously as pressure is exerted on the hand piece 34 the bell crank lever is rocked thereby rotating the gear wheel 27 through the pawl and ratchet connection, thus stepping the stencil sheet support forward a predetermined spaced distance. In order to effect the return movement of the handle to normal position a coil spring 37 is nested within a thinble 38 mounted over the end of the stud 25, where it is held in place by a nut 39 fitting over an upper threaded end 40 of the stud 25. The end of the coil spring 37 is seated in the hub 33 of the bell crank 45 lever.

In the operation of the stencil machine in which the carriage is mounted the feed carriage is stepped across the machine from right to left. When the carriage has reached the limit of movement it is returned by pressure on the hand piece 34 which pressure not alone returns the feed carriage to its starting point, but also advances the carriage inwardly a stepped distance for 50 line adjustment of the stencil sheet to the cutting point of the machine. Intermediate positions between the normal inward stepped movement of the stencil sheet support may be accomplished by manually moving the stencil sheet support forwardly or rearwardly by engagement of the hand with the stud 24.

I am aware that the invention may be modified in certain particulars without departing from the spirit and scope of the invention. I do not limit myself therefore to the exact details of construction shown and described.

What I claim and desire to secure by Letters Patent, is:

1. A feed carriage for stencil machines including a stencil sheet support movable toward and away from the cutting point of the machine, a mounting for the support arranged to be set at any lateral position to present the work to the cutting point at any point throughout the width of the sheet and to frictionally hold the same in its set position, and independent manipulative means 125

connected with said mounting adapted to space said support predetermined line spaces incident to the return of the carriage to starting position.

5 2. A feed carriage for stencil machines, comprising a table for the stencil sheet, a stencil sheet support movable across the table having means thereon for engaging the stencil sheet, a housing at one end of said 10 table, a guideway in the housing, a plate attached to the stencil sheet support operable in said guide way, means for adjusting the support transversely of said housing, and frictional means for holding the stencil sheet 15 support against displacement after it has been adjusted.

3. A feed carriage for stencil machines, comprising a table for the stencil sheet, a stencil sheet support movable across the table having means thereon for engaging the stencil sheet, a housing at one end of said table, a guide way in the housing, a plate attached to the stencil sheet support operable 20 in said guide way, means for adjusting the support transversely of said housing, frictional means for holding the stencil sheet 25 support against displacement after it has support against displacement after it has

been adjusted, a handle carried by said housing, a vertical support for said handle, and connecting means between the handle and said plate whereby said pressure on the handle to return the stencil sheet support to initial position actuates the support inwardly. 30

4. A feed carriage for stencil machines, comprising a table for the stencil sheet, a stencil sheet support movable across the table having means thereon for engaging the stencil sheet, a housing at one end of said table, a guide way in the housing, a plate attached to the stencil sheet support operable 35 in said guide way, means for adjusting the support transversely of said housing, frictional means for holding the stencil sheet support against displacement after it has been adjusted, a handle carried by said housing, a vertical support for said handle, connecting means between the handle and said plate whereby said pressure on the handle to return the stencil sheet support to initial position actuates the support inwardly, and 40 means limiting the stroke of the handle to determine the distance of the inward movement of said stencil sheet support. 45 50
